Charles C. Savery,
By his Atty,
J. S. Brown

United States Patent Office.

CHARLES C. SAVERY, OF PHILADELPHIA, PENNSYLVANIA.

Design No. 4,274, dated August 2, 1870.

DESIGN FOR A REFRIGERATOR AND WATER-COOLER.

The Schedule referred to in these Letters Patent and making part of the same.

To all whom it may concern:

Be it known that I, CHARLES C. SAVERY, of the city and county of Philadelphia, and State of Pennsylvania, have invented a new and original Design for a Refrigerator and Water-Cooler; and I do hereby declare that the following is a full and exact description thereof, reference being had to the accompanying drawing making part of this specification—

Figure 1 being a view of the refrigerator in perspective;

Figure 2, a central longitudinal vertical section thereof;

Figure 3, a transverse vertical section of the same through the ice-chamber and water-tank.

Like letters designate corresponding parts in all of the figures.

The refrigerator is composed of a rectangular iron box, A, enameled on the inside, surrounded and inclosed by a pine, or other kind of wooden case, B, with a suitable non-conducting air-space and packing between. The box has an opening in one end or one side, for a door, C, and an opening in a part of the top, to gain admission to the ice-chamber D, water-tank E, and a separate milk and butter-chamber, G. Or there may be a door in front, for each of the chambers G, H.

The ice-chamber D extends across the whole width and depth of the enameled box A, dividing it into two compartments or chambers, namely, the said milk and butter-chamber G, and the main refrigerating-chamber H. The milk and butter-chamber is quite narrow, as shown, so as to leave as much room as possible in the main chamber H.

The ice-chamber is either of galvanized or enameled iron, and fits the sides and bottom of the enameled box A closely, and may be secured therein either by soldering or rivets; and it may be secured to the top of the box by flanches a a. It is preferably made narrower at the bottom than at the top, so that the ice will not settle down so fast, and in order that the drip from the ice may run down its sides, and assist in cooling the same; or it can be made of uniform width.

The water-tank E is a separately-made vessel, of iron, enameled on both surfaces, inside and outside. It is made of the proper size to fit into the ice-cham-

ber at one end, occupying only a comparatively small part of the length thereof, and reaching down about one-half of the depth of the same, more or less. The water is drawn from it through a pipe, e, which extends laterally through the ice-chamber to, and thence through, the side of the refrigerator, and terminates outside with a spigot, d, whereby the water is drawn. This pipe not only is cooled by extending through the ice-chamber, but in this way can pass through the side of the enameled box, and make a tight joint with a jam-nut and washer, or otherwise. No ice is put in the water-tank, but the water is cooled by the tank being inside of the ice-chamber, in contact with the ice.

Just over the pipe e a shelf or grate, f, is placed in the ice-chamber, to support the ice. It is scalloped on its edges, or otherwise formed so as not to fit closely to the sides of the chamber, in order that the water from the melting of the ice may trickle down the sides of the chamber, and thereby increase the refrigerating effect. Instead of simple ice, a mixture of ice and common salt, or other freezing mixture, used in the ice-chamber, greatly enhances the refrigerating power, so that moisture condensed on the surface of the ice-chamber, in the chambers G and H, is frozen. The water from the melted ice is drawn off through a pipe, i, and spigot l, at one end of or under the refrigerator.

The top of the box A is not only enameled on the inside, but for a little distance around the top opening also, on the outside, so that no rusting of the iron may take place from the water and moisture of the ice-chamber and water-tank.

There are metallic covers, m, n, o, to the ice-chamber, water-tank, and the milk and butter-chamber, and above them is an air-space, and then a wooden cover, p, in the top of the refrigerator case, flush therewith on top.

What I claim as my invention, and desire to secure by Letters Patent, is—

The design for a refrigerator, as represented and described.

CHARLES C. SAVERY.
